UNITED STATES PATENT OFFICE.

EUGÈNE TÜLLER, OF STE. CROIX, SWITZERLAND, ASSIGNOR TO M. J. PAIL-LARD & CO., OF NEW YORK, N. Y.

MUSIC-BOX.

SPECIFICATION forming part of Letters Patent No. 364,554, dated June 7, 1887.

Application filed April 13, 1887. Serial No. 231,569. (No model.)

To all whom it may concern:

Be it known that I, EUGÈNE TÜLLER, of Ste. Croix, Canton de Vaud, in the Republic of Switzerland, have invented certain new and 5 useful improvements in Music-Boxes, of which the following is a specification.

This invention relates to certain new and useful improvements in that class of music-boxes in which the cylinder can be removed 10 from the music-box and replaced by another.

The object of my invention is to provide a new and improved music-box of this kind which is simple in construction, permits of removing and replacing the cylinder very easily 15 and rapidly, and which works perfectly.

The invention consists in the combination, with a comb and driving-gear, of suitable supports for the shaft of the removable cylinder and a spring-latch for holding the cylinder in 20 place and pressing it longitudinally; in the manner that will be fully described and set forth hereinafter, and finally pointed out in the claims.

In the accompanying drawings, Figure 1 is 25 a plan view of my improved music-box. Fig. 2 is a longitudinal detail view of the latch at one end, parts being in section. Fig. 3 is a detail view of the inner end of the latch. Fig. 4 is a detail side view of that end of the cylinder opposite the one shown in Fig. 2, parts of the driving-gear being in section. Fig. 5 is an inside view of the driving-wheel, the cylinder-shaft being in section.

Similar letters of reference indicate corresponding parts.

The comb A is fastened on the base-plate A' in the usual manner. The usual springs are contained in one or more spring-barrels, B, of the usual construction, one of which is provided with a cog-wheel, C, engaged with a pinion, D, on a tubular shaft, E, which is mounted to revolve on a fixed shaft, F, said tube E being also provided with a bearing, E'. On one end of the tubular shaft E the cog-wheel G is mounted, through the center of which the fixed shaft F projects, and said fixed shaft has a recess, F', in its end for receiving one pointed end of the shaft H of the cylinder J, which will be described hereinafter.

The usual retarding-gear, I, is operated by

suitable transmitting-wheels from the wheel G. On the wheel G a disk, K, is held by means of pins K', or otherwise, and is provided with a U-shaped or like notch, L, extending from the rim to the center and serving to receive the lug M, fastened on the end of the shaft H, said lug being provided with a handle-button, N. The usual spring, O, for pressing the cylinder longitudinally, is mounted on the shaft H, between the lug M and the end of the cylinder J. On the opposite end of the cylinder-shaft the wheel P is mounted, which is shown toothed, but need not necessarily be toothed, the teeth only serving to facilitate the subdivision of the cylinder. On the inner face of said wheel P the usual ratchet-wheel or cam, Q, is pivoted, which acts upon a pinion on the end of the cylinder for the purpose of shifting the cylinder longitudinally on its shaft to change the tune.

The wheel P is provided with a handle-knob or button, R. That end of the shaft adjacent to the wheel P is pointed and adapted to pass into a notch or recess in the end of the sliding latch S, mounted to slide in a casing, T, provided in its top with an inclined slot, U, having a notch, V, at one end, through which slot a rod, a, passes, which projects from the sliding latch S, the said latch S being surrounded by a spring, b, which presses it toward the end of the cylinder-shaft. On that end of the casing T adjacent to the wheel P an open U-shaped bearing, m, is formed, the bottom of which is round and serves as a support for the cylinder-shaft and the outer end of the latch S.

The operation is as follows: Fig. 1 shows the cylinder in place in the box. When it is desired to remove the cylinder, the rod a is moved in the direction of the arrow x', along the slot U, and then pushed into the notch V of the same, whereby the latch S is withdrawn and locked in place, and the spring b is compressed. The left-hand end of the cylinder-shaft is thus disengaged from the latch, and the cylinder and its shaft can be lifted out by means of the buttons or knobs N and R. The new cylinder is now put in place, the lug M on the right-hand end of the cylinder passing into the notch L of the disk K, and the left-

hand end of the shaft passes into the open bearing *m*. The rod *a* is then withdrawn from the notch *V* of the slot *U*, and the spring *b*, acting on the latch, presses the same longitudinally and against the left-hand end of the shaft, whereby the shaft is pressed longitudinally and the right-hand end of the cylinder-shaft is pressed against the end of the shaft *F*. The pins on the cylinder will then be in proper position in relation to the teeth of the comb. When the wheel *K* is revolved by the motor, it carries the lug *M* around with it, and thus revolves the shaft and cylinder.

Having thus described my invention, I claim as new and desire to secure by Letters Patent—

1. In a music-box, the combination, with a driving-gear, comb, cylinder, and cylinder-shaft, of a notched disk driven by the driving-

gear, a handle-lug on the cylinder-shaft fitting in the notch of said disk, and a spring-latch 20 acting on the opposite end of the cylinder-shaft, substantially as shown and described.

2. In a music-box, the combination, with a driving-gear, comb, cylinder, and cylinder-shaft, of a fixed shaft, *F*, a tubular shaft, *E*, 25 on the same, the pinion *D* on the tubular shaft, the wheel *G*, carrying the notched disk *K*, and a spring-latch acting on one end of the shaft, substantially as shown and described.

In testimony that I claim the foregoing as 30 my invention I have signed my name in presence of two subscribing witnesses.

EUGÈNE TÜLLER.
